United States Patent Office

Des. 176,233
Patented Nov. 29, 1955

176,233

SOAP CONTAINER

Mathias Schultz, San Francisco, Calif.

Application May 19, 1955, Serial No. 36,124

Term of patent 7 years

(Cl. D4—3)

Fig. 1.

Fig. 2.

Fig. 1 is a perspective view of a soap container, showing my new design; and

Fig. 2 is a similar perspective view with the device in a partly opened position.

I claim:

The ornamental design for soap container, as shown.
